UNITED STATES PATENT OFFICE

2,676,100

METHOD AND APPARATUS FOR
REPRODUCING IMAGESWilliam C. Huebner, Mamaroneck, N. Y., assignor
to The Huebner Company, Dayton, Ohio, a cor-
poration of Ohio

Application February 2, 1952, Serial No. 269,655

29 Claims. (Cl. 95—1.9)

1

This invention relates to a process and apparatus for reproducing or printing images such as texts, illustrations, symbols and the like on print receiving material.

An object of the invention is to provide a method and apparatus for printing or reproducing on print receiving material images such as texts, illustrations, symbols and the like wherein the reproduction or printing of the image is accomplished directly from the copy to the print receiving material in final and complete form.

Another object is to provide a method and apparatus as referred to above and wherein the need for the usual or conventional printing plates, inking apparatus, driers and the like is eliminated and consequently the labor and material costs incident to the preparation and use of such plates, apparatus and the like are eliminated.

Another object is to provide a method and apparatus as hereinbefore referred to and wherein the reproduced or printed images on the print receiving material are in final form and do not require drying or further processing or finishing operations.

A still further object is to provide a method and apparatus such as previously referred to and wherein the reproduced or printed image may have any desired size relationship with respect to the copy image.

A still further object is to provide a method and apparatus as hereinbefore referred to and wherein the reproduced or printed image on the print receiving material is not reversed with respect to the copy image.

A still further object is to provide a method and apparatus of the character referred to and wherein the print receiving material and the image copy may be substantially spaced apart and the image reproduced or printed on the material without contact between the material and the image copy and without the necessity of inking the image copy, or of having means for migrating ink from the image copy to the print receiving material and then subsequently drying the migrated ink on the receiving material.

A still further object is to provide a process and apparatus as hereinbefore referred to and wherein the image copy may be either light reflecting or light transmitting as, for instance, opaque copy or transparent copy.

A still further object is to provide a process and apparatus as hereinbefore referred to and wherein the reproduced image on the print receiving material may be a monochromatic reproduction or a multicolor reproduction.

2

A general object is to provide a method and apparatus for reproducing an image on print receiving material from image copy which is efficient, expeditious, economical and requires relatively simple apparatus and avoids the usual "make ready" required in ordinary printing and also eliminates the drying and other finishing operations required in ordinary printing, particularly in multi-color printing.

10 Further and additional objects and advantages not hereinbefore referred to will become apparent hereinafter during the detailed description of an embodiment of the invention which is to follow and which is illustrated in the accompanying drawing wherein,

Fig. 1 is a diagrammatic, partial elevation and partial section illustrating an apparatus embodying the invention and capable of carrying out the method.

20 Fig. 2 is a partial plan view of the apparatus shown in Fig. 1, with certain portions broken away and shown in section.

Fig. 3 is a fragmentary view taken substantially on line 3—3 of Fig. 1 looking in the direction of the arrows.

25 Fig. 4 is a fragmentary sectional view showing a modified form of target, and

Fig. 5 is a fragmentary detached elevation of the modified target shown in Fig. 4.

30 The invention contemplates directly reproducing or printing images in finished form on print receiving material utilizing transparent or opaque image copy. The image copy will have light transmitting or light reflecting image areas.

35 A light source of suitable wave length is utilized to pass light rays through the light transmitting portions of the copy or to reflect light rays from the light reflecting image portions of the copy as the case may be. These light rays will vary in intensity in accordance with the light transmitting or reflecting properties of the different portions of the image areas of the copy. The light rays are passed through or reflected from successive narrow zones of the image copy as the copy moves past the light source.

40 The transmitted or reflected light rays from each successive zone of the image copy are projected through a reversing lens and upon a photoelectric target to render radiant areas of the target correlated to the image areas of the copy. The photoelectric target will be selected to be responsive to the wave length of the light rays and is located at the printing zone and is spaced a predetermined distance from the print receiving material.

45 The term "printing zone" as used herein means

the space between the target and the print receiving material and the inlet and outlet points for the reproducing material later to be referred to.

The light rays striking the target and creating radiant areas thereon corresponding to the image areas of the copy cause streams of electrons to be emitted from the target and in paths extending toward the print receiving material. The intensity of said streams of electrons is directly proportional to the radiation of the target. The non-radiated areas of the target from which no electrons are emitted correspond to the non-image areas of the copy.

In order to accelerate the emission of the streams of electrons from the target and to the print receiving material an accelerating potential differential is set up between the target and the print receiving material. This is accomplished by associating with the target on the side thereof away from the print receiving material a transparent electrically conductive means such as a film of metal to which is connected one pole of an electrical circuit of suitable potential, as for instance the negative pole thereof. The other pole of said circuit is connected to an electrode located on the opposite side of the print receiving material from the target. The electrical circuit used will be of very low amperage with a voltage range between 2,000 and 10,000 volts and will have no function independently of accelerating the emission of electrons from the target.

Simultaneous with the emission of the streams of electrons from the light sensitive target reproducing material in cloud-like-form such as smoke (combustion or chemical) mist, vapor or the like, is passed through the printing zone from the inlet side thereof to the outlet side. This reproducing material has a precharge imparted thereto of a polarity corresponding to that of the electrode and as the material passes through the printing zone it is propelled or acted upon by the emitted streams of electrons and migrates to and is impregnated in the print receiving material in areas corresponding to the image areas of the copy. It has been found that the emitted streams of electrons acting on the positively charged reproducing material dynamically drive the material against and into the print receiving material so that the reproducing material is immediately integrated with the print receiving material and will not rub off or smear and need not be given any drying, heating or other finishing operation.

The density of the pigmentation integrated into the print receiving material by the migrated reproducing material and in areas corresponding to the image areas of the copy will be directly proportional to the light transmitting or light reflecting characteristics of the image areas of the image copy so as to produce the desired tonal qualities and variations in the reproduced image.

It is proposed to utilize an image copy in the form of a web moving in predetermined timed relation to a moving web of print receiving material. The transmitted or reflected light rays from the successive zones of the image copy as it continuously passes a given point function to reproduce the image areas of said zones on corresponding successive zones of the continuously moving web of print receiving material. As an example, if the image copy contains printed or typewritten texts the successive zones thus re-

produced on the receiving material may be successive lines of the text.

It is further contemplated to employ a plurality of webs of image copy each web having image areas corresponding to a different color portion of the image. These webs of image copy may be utilized successively to reproduce on the print receiving material in the desired colors the image areas of the image copy webs, it being understood that different colored reproducing material will be passed through the printing zone as each different image copy web is employed.

It will also become apparent hereinafter that suitable registration for the different colored image areas on the webs of image copy is effected on the print receiving material to produce a multicolor print or reproduction on the receiving material.

The reproduced image either in monochromatic or multicolor form may be of the same size as the image copy or of a different size depending upon the adjustment given to the lens along its focal axis, it being understood that the print receiving material will move at the same or different speeds with respect to the rate of movement of the image copy depending upon the size of the reproduced image. If the image areas of the image copy are light transmitting or reflecting areas said areas will be reproduced on the print receiving material by the reproducing material. If the non-image areas of the image copy are light transmitting or light reflecting areas then said non-image areas will be reproduced on the print receiving material by the reproducing material.

A suitable apparatus for reproducing or printing images in accordance with the present invention is shown in the drawing for illustrative purposes. This apparatus comprises a suitable frame 10, portions of which are indicated in Fig. 2. The frame 10 mounts a stationary shaft 11 on which an image copy cylinder 12 is rotatably supported by means of end plates 13, said end plates being rotatably mounted on the shaft 11 by means of suitable bearings. The cylinder 12 is preferably transparent, being formed of suitable light transmitting plastic or other material. A hood 14 which is substantially triangular in cross section is located within the cylinder 12 and extends the axial length thereof and is fixedly supported on the stationary shaft 11 by means of a suitable supporting bracket 15. The hood 14 has its wall adjacent to the inner circumference of the cylinder 12 curved concentrically to the cylinder and said wall portion of the hood intermediate its ends is provided with a narrow slot 16 extending the longitudinal length of the hood. An elongated light tube 17 is supported in the hood 14 and extends the longitudinal length thereof and is located in line with the slot 16. The light tube 17 is connected to an electrical circuit later to be referred to and it will be understood that the wave length of the light produced by the tube 17 is predetermined in relation to the wave length sensitivity of the photoelectric target later to be referred to.

An arcuate reflector 18 is supported in the hood 14 in line with the light tube 17 and the slot 16 so as to reflect the light rays from the light 17 through the slot 16 and through the transparent cylinder 12 as the latter rotates past said slot. The cylinder 12 is rotated by providing on the circumference of one of the end plates 13 suitable helical gear teeth 19 which mesh with a gear 20 fixed to a drive shaft 21 rotatably supported

in the frame 10 and driven by any suitable power source. The drive shaft 21 extends to a variable speed transmission 22 later to be referred to.

The frame 10 supports a cylinder 23 for the print receiving material, said cylinder 23 being spaced from the cylinder 12 longitudinally of the frame. The cylinder 23 preferably is formed of metal and is mounted upon suitable end plates 24 similar to the end plates 13 for the cylinder 12 with said cylinder 23 electrically insulated from the end plates 24 as will be well understood in the art.

The end plates 24 are rotatably supported by means of suitable bearings on a stationary hollow shaft 25 mounted in the frame 10 and parallel to the shaft 11. One of the end plates 24 is provided with helical gear teeth 26 on its circumference which mesh with a gear 27 fixed to a drive shaft 21a rotatably mounted in the frame 10 and extending longitudinally thereof. The drive shaft 21 extends to the variable speed transmission 22 and the latter operatively interconnects the drive shafts 21 and 21a so that the shaft 21a may be operated by the shaft 21 at the same or different speeds, depending upon whether the reproduced image is of the same size or a different size with respect to the image copy.

The image copy indicated at 28 and the print receiving material indicated at 29 are illustrated as in the form of webs and in order that the image copy and the print receiving material will move in accurately timed relationship said copy and said material are provided along their edges with openings accurately and identically spaced longitudinally of the copy and material and cooperating with accurately and identically spaced projections 30 formed on the circumferences and adjacent the ends of the image copy cylinder 12 and the print receiving material cylinder 23. The spaced openings and the projections 30 just referred to maintain the predetermined relationship required between the image copy and the print receiving material and are particularly important when multicolor reproductions are being made as they maintain the proper registration of the different colored image portions with the corresponding portions of the print receiving material.

Intermediate the cylinders 12 and 23 the frame 10 supports a suitable lens indicated at 31. This lens may take the form of the reversing lens disclosed in my United States Patent 2,408,855, issued October 8, 1946, and the description contained in said patent of said reversing lens is incorporated herein by reference.

The lens 31 is supported on upstanding portions 32 of a supporting plate 33, the opposite ends of which are slidably supported for adjustment purposes in channels formed in upstanding walls of a base 34. It will be seen that the lens 31 can be adjusted from a mid position to either side thereof longitudinally of its focal axis and it will be understood that suitable means, not shown, may be provided for locking the lens in any adjusted position. The focal axis of the lens 31 is aligned with the opening 16 in the light hood 14.

The frame 10 supports adjacent to the cylinder 23 an inlet hood 35 and an outlet hood 36. These hoods are each provided with a curved wall portion adjacent to the circumference of the cylinder 23 and said curved wall portions cooperate with interior walls of the hoods to form respectively an inlet nozzle 37 and an outlet nozzle 38 located on opposite sides of the printing zone and

spaced apart substantially the width of the printing zone, it being recalled that said printing zone is the space or gap between the cylinder 23, the nozzles 37 and 38 and the photoelectric target 5 later to be referred to.

The hoods 35 and 36 on their sides adjacent to the lens 31 are provided with thickened portions which support a transparent plate 39 that is covered on its side adjacent to the lens 31 with opaque material 40, except for a space indicated at 41 and constituting a slot in line with the focal axis of the lens 31 and the slot 16 of the light hood 14. The slot 41 extends the axial length of the cylinder 23. The transparent plate 39 on its side adjacent to the cylinder 23 supports a thin transparent metallic film such as an aluminum film indicated at 42 and having a central portion registering with the slot 41, it being understood that the plate 39 and film 42 extend the longitudinal length of the print receiving material 23.

The film 42 on its side adjacent to the cylinder 23 has a layer 43 of suitable photoelectric material. The central portion of the layer 43 registers 25 with the slot 41 and said layer also extends the longitudinal length of the cylinder 23 and the slot 41. The material of which the layer 43 is formed may vary in accordance with the wave length of the light rays produced by the light 30 17. While various photoelectric or light sensitive materials may be used to form this layer the layer will be referred to herein as a selenium layer for purposes of illustration although it might be formed of germanium or other suitable photoelectric material.

The transparent metallic film 42 is connected to the negative side of a suitable electric circuit indicated at 44. The positive side of the said circuit is indicated at 45 and is connected to an electrical conductor 46 mounted in but insulated from the tubular shaft 25 and said conductor is electrically connected to a blade-like electrode 47 within the cylinder 23 and located in the plane of the focal axis of the lens 31 and having a knife edge spaced from the inner circumference of the cylinder 23 and the said electrode extends the longitudinal length of the cylinder 23 and is suitably supported therein by the stationary shaft 25. The electrical circuit referred to provides 45 for an accelerating potential between the metallic film 42 and the electrode 45 to accelerate or facilitate the emission of electrons from the photoelectric layer 43 under the action of the light rays as will later be more fully explained. It 55 will be understood that the voltage of the electric circuit will be suitable to produce the accelerating potential desired.

On each side of the blade electrode 47 is a series of electric magnets, with the opposite poles of each electromagnet spaced from each other longitudinally of the cylinder and of the blade electrode 47, see Figs. 1 and 3. The series of magnets on one side of the electrode 47 is indicated at 48 and the series of magnets on the other side of the electrode is indicated at 49. The opposite poles of the magnets in both of the series are indicated at P and P' in Fig. 3. The opposite poles P and P' of the series of magnets are spaced from the electrode 47 a predetermined distance 60 and the magnetic field between the opposite poles P and P' of each magnet in the two series form continuous or overlapping parallel magnetic fields on each side of the electrode 47 throughout its longitudinal length and said continuous parallel magnetic fields form a magnetic shield ex-

tending longitudinally of the electrode and on opposite sides thereof. The magnetic fields of two of the magnets are indicated by dash lines in Fig. 3, and it will be noted that said fields overlap and hence each series of magnets produces in effect a continuous field extending longitudinally of the series.

The magnets 48 and 49 are provided with mounting portions 50 which embrace the tubular stationary shaft 25 and are clamped thereon by suitable clamping bolts 51, it being understood that a bar 52 is interposed between the ends of the mounting portions 50 to facilitate the clamping of said portions to the tubular shaft 25. An insulating sleeve 53 may be interposed between the shaft 25 and the mounting portions 50 of the magnet and also the part 52 might be formed of insulating material.

It will be understood that the windings of the magnets are connected to a suitable source of electric current in any conventional way. It will further be understood that the apparatus will function satisfactorily without the magnets and that the latter need not be used but it is felt that the use of the magnet produces improved results and particularly with respect to certain reproduction materials, certain print receiving materials and certain photoelectric layers and their use is recommended.

The magnetic fields on each side of the electrode 47, as already stated, function as shields and act to confine the flow of electrons across the gap of the printing zone to straight line flow corresponding to the light rays. The stated action of the magnetic shields is due to the fact that said shields confine the accelerating potential and prevent dispersion thereof.

The inlet hood 35 is connected with an inlet conduit 54 and the reproducing material in cloud-like-form is introduced into the hood 35 through said conduit. A precharging electrode 55 is located within the hood 35 and is connected by a lead 56 to the positive side of the accelerating current and said electrode 55 imparts a positive precharge to the material entering the hood 35 prior to said material passing through the inlet nozzle 37 into the printing zone. The electrode 55 is shown as in the form of bars which extend the longitudinal length of the hood 35, it being understood that said bars will be electrically insulated from the hood in any suitable and well known manner.

The conduit 54 may extend to a single source of supply of reproducing material if monochromatic reproductions are to be made or it may be selectively connected to a plurality of conduits 57, each of which extends to a separate source of supply of reproducing material as, for instance, in the reproduction of multicolor images the conduits 57 would extend to supply sources for reproducing material to produce the different desired colors.

The conduits 57 are connected to openings in a stationary plate 58 which is mounted in a rotatable cone-shaped connecting member 59 that has a plate 60 provided with a single opening which when the member 59 is rotated can be selectively aligned with any one of the openings in the plate 58 to connect the interior of the member 59 with any one of the conduits 57 as desired.

The cone-shaped member 59 is provided with a cylindrical extension interfitting the conduit 57 and interconnecting said conduit with the interior of the member. The outlet hood 36 is connected with a conduit 61 that extends to a suc-

tion device so that reproducing material which is not migrated to the print receiving material can be drawn from the printing zone through the nozzle 38, hood 36 and conduit 61 and said withdrawn material, if desired, may be recirculated to the conduit 54 or to the proper conduit 57 as the case may be.

The elongated light tube 17 in the light hood 14 is connected in an electrical circuit indicated by the leads 62 and 63 by suitable connecting wires 64 and 65. It will be noted that the connecting wires 64 extend to a double pole single throw switch 66 which is electrically connected to the lead 62 through an "on and off" rotatable commutator 67. The commutator 67 is provided on its circumference with insulating portions 68 and when said portions are in contact with the brushes of the commutator the circuit to the light 17 is interrupted. It will be understood that the commutator 67 is suitably insulated from its support and is rapidly rotated by any desired means and thus effects rapid make and break of the circuit to the light 17. This rapid make and break of the light circuit produces a pulsating effect so that the light source produced by the light can be designated as a pulsating light source although the rapidity of the pulsations is such that to the eye it would appear as a constant light source.

It has been found that the rapidly pulsating light source produces improved results and enables a sharper more clearly defined image to be reproduced. Of course, if it is desired to use a non-pulsating light source, then the commutator rotation can be stopped in a position wherein the brushes are not on the insulated portions 68 and a continuous circuit is maintained to the light.

It will be assumed first that a monochromatic reproduction is to be made in accordance with the method and by the apparatus described. It will also be assumed that the web 28 of image copy is moving with the cylinder 12 rotating in the counterclockwise direction as indicated by the arrow in Fig. 1.

The web of image copy has its image areas light transmitting and its non-image areas opaque. The web of print receiving material is moving in a downward direction with the clockwise rotation of the cylinder 23 as viewed in Fig. 1 and as indicated by the arrow.

It will be assumed that the image is to be reproduced the same size as the image of the copy and hence the lens 31 will be adjusted on its focal axis to its central or intermediate position between the cylinder 12 and the target 43. The switch 66 is closed to place the light 17 in the light circuit and if a pulsating light is to be used the rotation of the commutator 67 will be initiated. Also the cloud-like reproducing material in the form of smoke (combustion or chemical), mist or vapor is introduced through the conduit 54 into the inlet hood 35 and under slight pressure while the outlet hood 36 is under suction by the suction device connected to the conduit 61. As successive portions of the image copy 28 continuously move past the slot 16 the light rays from the light 17 pass through the slot 16, the transparent cylinder 12, the image areas of the copy, lens 31, slot 41, transparent metallic film 42 and strike the photoelectric layer or target 43 in areas corresponding to the image areas of the copy. The light rays thus striking the layer 43 cause streams of electrons to be emitted therefrom which travel toward the print

receiving material 29. The emission of the streams of electrons is accelerated by the accelerating potential between the transparent metallic film 42 and the electrode 47, it being understood that the electric circuit for creating said potential has been established. Also the cloud-like reproducing material entering the printing zone has received a positive charge and hence said material will be acted on by the accelerated streams of electrons and carried across to and impregnated in the print receiving material in areas corresponding to the image areas of the copy to thus reproduce on the continuously moving print receiving material the image areas of the continuously moving image copy.

The electromagnets 48 and 49 may or may not be energized depending upon whether it is desired or necessary to utilize their shielding action. The reproducing material which is not migrated to and impregnated in the print receiving material is drawn from the printing zone through the exhaust nozzle 38, hood 36 and conduit 61. It will be noted that the print receiving material has had any static electrical charges which might have been thereon removed before entering the printing zone by a suitable static eliminator 69. A second static eliminator 69 is employed to remove any residual charges from the print receiving material after it has passed through the printing zone and off of the cylinder 23.

In addition it will be understood that the cylinders 12 and 23 and the image copy 28 and print receiving material 29 rotate or move at the same speed and this is accomplished by the proper setting of the variable speed transmission 22, it being recalled that the synchronization in movement of the image copy 28 and the print receiving material 29 is assured by the use of the projections 30 formed on the circumferences of the cylinders and engaging in spaced openings in the image copy and print receiving material, it being understood that this prevents any slippage of the copy or the material with respect to the cylinders 12 or 23.

If the image to be reproduced is smaller or larger than the image on the image copy then the lens 31 will be adjusted along its focal axis to one or the other side of its intermediate position as the case may be while the variable speed transmission will be adjusted so that the speed of the cylinder 23 will be faster or slower than the speed of the cylinder 12 as will be well understood.

If it is desired to reproduce a multicolor image, as for instance an image of three colors, then three webs of image copy will be successively mounted on the cylinder 12 and moved past the slot 16. Each of the webs of image copy will have the image areas thereof corresponding to a particular color area for the reproduction.

The conduit 54 will be connected to one of the conduits 57 for a particular color correlated to the web of image copy currently being employed and the image areas of the copy representing the particular color will be reproduced in such color on the print receiving material in the manner already described with respect to the reproduction of a monochromatic image.

When the image areas correlated to one color have been reproduced on the print receiving material the web 28 of image copy is replaced by a web 28 having image areas corresponding to the second color and then the print receiving web is run through a second time with the sec-

ond image copy web to reproduce on the web 29 the image areas of the second copy, it being understood that the conduit 54 is connected to the conduit 57 which extends to the source of supply of print reproducing material for the second color. The same thing is repeated to reproduce the third color as will be apparent.

Inasmuch as the cylinders 12 and 23 are provided with the projections 30 engaging in the spaced openings in the image copy webs 28 and the printing receiving material web 29 and the cylinders are rotating in accurately predetermined speed relationship, it will be seen that proper registration is obtained between the image areas of the different colors.

If it is desired to employ a web of image copy having the image areas thereof light reflective rather than light transmitting then the light 17 in the light hood 14 is not used and in place thereof similar lights 70 are employed, said lights 70 being mounted in light directing shields 71 which project the light rays from the lights 70 onto successive portions of the image copy 28 which continuously pass through the focal axis 25 of the lens 31, it being noted that said lights 70 and shields 71 are located on opposite sides of the focal axis of the lens with the shields positioned to project the light rays onto the image copy in substantially the same area with respect to the lens focal axis.

The lights 70 are connected by wires 72 and 73 to the other pole of the two-pole switch 66 so that when said switch is thrown from the full line position indicated in Fig. 1 to the dash line position thereof the lights 70 will be electrically connected to the commutator 67. The lights 70 are connected to the lead 63 in the other side of the light circuit by wires 74 and 75.

In place of the transparent metallic film 42 and photosensitive target 43 heretofore described, the arrangement shown in Figs. 4 and 5 may be used. This arrangement constitutes a fine wire mesh or screen 76, such as a chrome nickel screen, the wires of which are coated with germanium or other light sensitive material. The screen 76 is connected in the electrical circuit as is the film 42 to provide for the accelerating potential, while the light sensitive material coating the wires serves the purpose of the target 43, it being understood that the light rays pass through the screen.

It will be understood that the method and the apparatus may be carried out or operated to reproduce images by reflected light rays similarly to the description heretofore set forth with respect to the reproduction of images by transmitted light rays and hence there is no necessity to repeat such description with respect to reflected light rays.

It will also be understood that the image areas of the image copy will have portions varying as to light transmitting or light reflecting ability and that the different densities of the light rays passing through such portions or reflected from such portions will cause the image to be reproduced on the print receiving material with correlated tonal or density variations so that the reproduced image will have light and dark portions and portions intermediate light and dark corresponding to the light and dark color densities of the original subject represented by the image copy.

The term "transparent" is used herein and in the claims as connoting the ability to trans-

mit light and includes not only clear transparency but also translucency.

The term "opaque" is used herein and in the claims to signify the ability to reflect light as contrasted to transmitting light.

The term "reproducing material in cloud-like form" is employed herein and in the claims with the significance of the definition of "cloud" in Webster's Unabridged-New-International Dictionary—second edition, namely, a visible assemblage of particles in the air or in a gas; as, a cloud of smoke or of dust or of mist or of vapor.

The term "smoke" is used herein and in the claims to indicate smoke created by combustion or smoke created by chemical action.

Although preferred forms of the invention have been described and illustrated herein, it will be understood that the invention may be embodied in other forms coming within the scope and meaning of the appended claims.

Having thus described my invention, I claim:

1. An apparatus for reproducing images directly on print receiving material from image copy which comprises an image copy support, a print receiving material support spaced from said copy support, a light sensitive target located adjacent to but spaced from said material support with an air gap therebetween, a lens located intermediate said supports and having its focal axis passing perpendicularly through said target, means for projecting light rays correlated to the image copy supported by said copy support through said lens and upon said target to cause the emission from the target of streams of electrons passing through the air gap and toward said material support and the print receiving material thereon, and means for introducing reproducing material in cloud-like form into the air gap intermediate said target and said material support to be acted on by the streams of electrons and migrated and propelled thereby toward said material support and the print receiving material thereon.

2. An apparatus according to claim 1 and wherein means is provided for adjusting said lens along its focal axis.

3. An apparatus according to claim 1 and wherein means is provided for creating a potential differential between said target and said material support to accelerate the emission of the streams of electrons from the target and which means includes a transparent metal film associated with that side of the target adjacent to the lens and connected to one pole of an electrical circuit and an electrode operatively associated with said material support and located on the side thereof remote with respect to said target and in the focal axis of said lens and connected to the other pole of said electrical circuit.

4. An apparatus according to claim 3 and wherein means is provided for shielding the streams of electrons and for confining the same to straight line paths and which includes a series of electromagnets arranged on opposite sides of said electrode.

5. An apparatus as defined in claim 3 and wherein means is provided for charging the reproducing material in cloud-like form with a charge of the same polarity as the polarity of the electrode.

6. An apparatus as defined in claim 1 and wherein the means for projecting the light rays includes means for rapidly pulsating said light rays with a predetermined frequency.

7. An apparatus as defined in claim 1 and wherein the supports for the image copy and for the print receiving material are rotatable cylinders, while an operative connection is provided between said cylinders to rotate the same in timed relationship and includes a variable speed transmission.

8. An apparatus as defined in claim 7 and wherein the image copy support is a transparent cylinder, while the means for projecting the light rays includes a light source arranged within said transparent cylinder and including a light housing having a reflector and a slot extending longitudinally of the transparent cylinder and located on the focal axis of the lens.

9. An apparatus for reproducing images as defined in claim 7 and wherein the means for projecting the light rays include light housings each having a light source therein and located exteriorly of the image copy cylinder support and positioned to direct light rays against the image copy carried by said cylinder support in an area thereof through which the focal axis of the lens passes.

10. An apparatus for reproducing images as defined in claim 7 and wherein the image copy cylinder support and the print receiving material cylinder support are each provided on its circumference with identically circularly spaced projections adapted to engage in correspondingly spaced openings formed in the image copy and the print receiving material to assure proper correlation of movement between the image copy and receiving material.

11. An apparatus for reproducing images as defined in claim 7 and wherein the means for introducing reproducing material in cloud-like form intermediate the target and the receiving material support includes a conduit and means for selectively connecting said conduit to a plurality of additional conduits each extending to a different supply source of reproducing material.

12. An apparatus for reproducing images directly on print receiving material from image copy which comprises an image copy support, a print receiving material support spaced from said copy support, a light sensitive target located adjacent to but spaced from said material support by an air gap, a transparent metal film associated with that side of the target remote to the material support and connected to one pole of an electrical circuit and contacting said target, an electrode operatively associated with said material support and located on the side thereof remote with respect to said target and connected to the other pole of said electrical circuit, said metal film and said electrode creating a potential differential between said target and said material support, a lens located intermediate said supports and having its focal axis passing perpendicularly through said target, means for projecting light rays correlated to the image copy supported by said copy support through said lens and upon said target to cause the emission from the target and across the air gap of streams of electrons extending toward said material support and the print receiving material thereon and accelerated by the said potential differential, and means for introducing material in cloud-like form into the air gap intermediate said target and said material support to be acted on by the streams of electrons and migrated and propelled thereby toward said material support and the print receiving material thereon.

13. An apparatus for reproducing images di-

rectly on print receiving material from image copy which comprises an image copy support, a print receiving material support spaced from said copy support, a fine mesh wire screen located adjacent to but spaced from said material support by an air gap and having the wires thereof coated with a light sensitive material, a lens located intermediate said supports and having its focal axis passing perpendicularly through said screen, means for projecting light rays correlated to the image copy supported by said copy support through said lens and upon said screen to cause the emission from the screen of streams of electrons extending across the air gap toward said material support and the print receiving material thereon, means for introducing reproducing material in cloud-like form into said air gap intermediate said screen and said material support to be acted on by the streams of electrons and migrated and propelled thereby across the air gap toward said material support and the print receiving material thereon, an electrode operatively associated with said material support and located on the side thereof remote with respect to said screen and in the focal axis of said lens and connected to one pole of an electrical circuit, said screen being connected to the other pole of said electrical circuit wherefore said screen and said electrode create a potential differential between said screen and said material support that accelerates the emission of the streams of electrons from the screen.

14. The method of reproducing images directly on print receiving material from image copy which comprises projecting light rays correlated to the image copy through a lens and upon a light sensitive target to cause the emission therefrom of streams of electrons in areas correlated to the image copy, simultaneously positioning the print receiving material closely adjacent to the electron emitting surface of the target but spaced therefrom by an air gap and in the path of said streams of electrons that are flowing across the gap, wherefore the electrons directly strike the print receiving material, and simultaneously introducing into said air gap between the target and the print receiving material reproducing material in cloud-like form to be acted upon by the streams of electrons and migrated and propelled thereby to the print receiving material to form directly on the surface thereof adjacent to the target the finished reproduced image.

15. The method of reproducing images directly on print receiving material from image copy as defined in claim 14 and wherein the light rays correlated to the image copy are projected through a reversing lens and upon the light sensitive target to cause the emission therefrom of streams of electrons in areas correlated to the image copy and of the same order.

16. The method of reproducing images directly on print receiving material from image copy as defined in claim 14 and wherein the projected light rays are rapidly pulsated at a predetermined frequency.

17. The method of reproducing images directly on print receiving copy as defined in claim 14 and wherein the light rays are transmitted through transparent image copy and through a lens and upon the light sensitive target to cause the emission of streams of electrons in areas correlated to the image copy.

18. The method of reproducing images directly on print receiving material from image copy as defined in claim 14 and wherein the light rays are

reflected from opaque image copy and through a lens and upon the light sensitive target to cause the emission from the target of streams of electrons in areas correlated to the image copy.

5 19. The method of reproducing images directly on print receiving material from image copy as defined in claim 14 and which includes creating spaced parallel magnetic fields which shield the streams of electrons and cause the same to follow

10 straight confined paths.

20 20. The method of reproducing images directly on print receiving material from image copy as defined in claim 14 and wherein a potential differential is created between the target and a location

15 on the remote side of the print receiving material to accelerate the emission of the streams of electrons from the target and directly to the print receiving material.

21. The method of reproducing images directly on print receiving material from image copy as defined in claim 20 and which includes imparting to the reproducing material before it is introduced into the air gap an electrical charge of a polarity such that the potential differential which

25 accelerates the emission of the streams of electrons from the target will facilitate the migration and propulsion of the reproducing material by the streams of electrons to the print receiving material.

30 22. The method of continuously and successively reproducing images directly on successive areas of webs of print receiving material from successive corresponding areas of webs of image copy which comprises moving the webs of print

35 receiving material and of the image copy in timed relationship to each other, simultaneously projecting light rays correlated to the successive areas of the moving web of image copy through a lens and upon a light sensitive target to cause

40 the successive emission therefrom of streams of electrons correlated to the successive areas of the image copy and with the corresponding successive areas of the moving web of print receiving material located closely adjacent to the target but

45 spaced from the electron emitting surface thereof by an air gap and in the path of said streams of electrons flowing across the gap whereby the electrons directly strike the surface of the said successive areas of the moving web of print receiving material that is adjacent to the target, and simultaneously introducing into said air gap between the target and the print receiving material reproducing material in cloud-like form to

50 be acted on by the streams of electrons and migrated and propelled thereby to the corresponding successive areas of the moving web of print receiving material to form continuously and directly and successively on the surface thereof adjacent to the target the finished reproduced images correlated to the successive areas of the image copy.

55 23. The method of continuously and successively reproducing images directly on successive areas of webs of print receiving material from successive corresponding areas of webs of image copy as defined in claim 22 and wherein the light rays correlated to the successive areas of the moving web of image copy are transmitted through transparent portions of said web of image copy and through the lens and upon the light sensitive target.

60 24. The method of continuously and successively reproducing images directly on successive areas of webs of print receiving material from successive corresponding areas of webs of image

75

copy as defined in claim 22 and wherein the light rays correlated to the successive areas of the moving web of image copy are reflected from opaque portions of said web of image copy and through the lens and upon the light sensitive target.

25. The method of continuously and successively reproducing images directly on successive areas of webs of print receiving material from successive corresponding areas of webs of image copy as defined in claim 22 and wherein spaced parallel magnetic fields are created to shield the streams of electrons and cause the same to follow straight confined paths across the gap.

26. The method of continuously and successively and directly reproducing images on successive areas of webs of print receiving material from successive corresponding areas of webs of image copy as defined in claim 22 and wherein a potential differential between the target and a location on the remote side of the print receiving material is created to accelerate the emission of the streams of electrons from the target across the gap to the print receiving material.

27. The method of continuously and successively and directly reproducing images on successive areas of webs of print receiving material from successive corresponding areas of webs of image copy as defined in claim 26 and wherein an electrical charge is given to the reproducing material prior to its introduction to the air gap and of a polarity correlated to said potential differential such that the migration and propulsion of the reproducing material by the streams of electrons to the print receiving material is facilitated.

28. The method of reproducing images directly on print receiving material from image copy and of the same size as or of a different size than the image copy which comprises projecting light rays correlated to the image copy through a lens and upon a light sensitive target to cause the emission therefrom of streams of electrons in areas correlated to the image copy, adjusting the lens along its focal axis to obtain the desired size of reproduced image with respect to the size of the image copy, simultaneously with the emission of the streams of electrons from the target positioning the print receiving material closely adjacent to the electron emitting surface of the target but spaced therefrom by an air gap and in the path of said streams of electrons that are flowing across the gap, wherefore the electrons directly strike the surface of the print receiving material that is adjacent to the target, and simultaneously introducing into said air gap intermediate the target and the print receiving

material reproducing material in cloud-like form to be acted upon by the streams of electrons and migrated and propelled thereby to the surface of the print receiving material that is adjacent to the target to form directly thereon the finished reproduced image.

29. The method of reproducing multicolored images directly on a web of print receiving material which comprises successively moving the web of print receiving material in timed and predetermined relationship to a plurality of webs of image copy each having image areas correlated to a different one of the multicolors of the reproduced image, successively projecting light rays correlated to the image areas of each of the moving webs of the image copy through a lens and upon a light sensitive target to cause the emission therefrom of streams of electrons correlated to the image areas of each web of image copy, simultaneously and successively positioning the moving print receiving material closely adjacent to the electron emitting surface of the target but spaced therefrom by an air gap and in the path of said streams of electrons that are flowing across the gap, wherefore the electrons directly strike the surface of the print receiving material that is adjacent to the target, simultaneously and successively introducing reproducing material of the desired color and in cloud-like

30 form into said air gap intermediate the target and the print receiving material to be acted upon by the streams of electrons and migrated and propelled thereby to the moving web of print receiving material to form directly and successively on the surface thereof adjacent to the target the portions of the reproduced images of the various desired color and corresponding to the image areas of the webs of image copy.
